UNITED STATES PATENT OFFICE.

CHRISTIAN B. JOHNSON, OF SEATTLE, WASHINGTON.

COMBINED IRONING BOARD AND CLOTHES RACK CABINET.

Application filed April 4, 1927. Serial No. 180,763.

My invention relates to ironing boards and clothes racks of the type which are incorporated in a cabinet, this being usually built into the wall of a house.

5 The object of my invention is to provide additional improvements to devices of this sort, and particularly to provide means whereby the clothes rack is automatically raised by the lowering of the ironing board, 10 and by which the clothes rack may be maintained in raised position even if the ironing board be swung upward or closed into the cabinet.

Another object of my invention is to provide 15 a supporting leg and means for connecting it with the ironing board, so that it may be placed in a diagonal position extending back under the ironing board or towards its inner end, or, when desired, may be brought 20 out and applied as a vertical post under the ironing board, well outward towards its outer end.

Other objects of my invention will be determined by a study of the specification and 25 the accompanying drawings.

The accompanying drawings illustrate my invention as I now prefer to make it.

Figure 1 shows a side view of my device, the enclosing cabinet being shown in section 30 and the ironing board down, and the clothes rack up;

Figure 2 is a front elevation of the device with the parts enclosed in the cabinet and the front of the cabinet open;

35 Figure 3 is a similar view, except that the parts of the device are in opened or position of use.

This invention is specifically designed as an improvement upon Patent No. 1,277,599, 40 issued September 3, 1918, to John Bjork Johnson. The general features of construction of this device are along the line of that shown in said patent. In the drawings, 1 represents a cabinet or casing which is designed to be inserted in the wall of a building. In this is mounted an ironing board 2, this being journaled upon a transversely extending pivot rod 12 carried by the side walls of the casing or cabinet. The board is 45 provided with two bearing plates 20, which extend over the pivot bar 12 and form the bearings upon which the board turns. To fixedly position the board against side movement while leaving it free to move without 50 engagement with the sides of the cabinet, I prefer to provide the bearing plates 20 each

with a lateral extension 21, which extends far enough outwardly to bear against the side wall of the casing, or against a wear plate carried thereby. By this expedient the 60 board is safely positioned against lateral movement, while permitting ample clearance against the side edges while being inserted in or removed from the cabinet.

The ironing board, when lowered into position of use, is supported by a brace or leg 3. I have shown a method of attaching this to the ironing board which permits of this supporting leg or brace being placed in either of two positions. One position, which is shown in full lines in Figure 1, has the leg 3 in vertical position and engaging the ironing board well towards the outer end thereof. The other position, which is shown in dotted lines in the same figure, has the 70 post 3 placed in a diagonal position, the lower or inner end thereof extending into the bottom of the cabinet and engaging with a thrust block 11. The upper or outer end of the post 3 engages with the inner end of a block 22 carried by the under surface of 80 the ironing board so as to provide a substantial abutment against which the upper end of the post may bear.

The post 3 is secured to the ironing board 85 by means of a link 30, this preferably being made of a U shape and pivoted at 23 to the ironing board or to the block 22 carried thereby. It is also pivoted at 24 to the post, itself, this pivot point being located a short 90 distance downward from the upper end of the post. By reason of this mounting, it is evident that the post may be swung outward into the position shown in full lines in Figure 1, in which position it forms a substantial and vertical leg, or it may be swung backward and under the ironing board, so as to form a diagonal brace, as is shown by the dotted lines.

At the upper end of the cabinet 1 is 100 placed a clothes rack. This comprises a base plate 5 pivoted at 31 to swing in the cabinet. This is provided with a series of fingers or bars 50, which are pivoted as by bolts 52, so that they may swing horizontally 105 when the device is in position of use. This clothes rack is controlled in position by links or rods as 66, which are pivoted to the base member 5 and also to a bar 6 which is mounted to slide in guides, as 60, carried 110 by the back wall of the cabinet. This rod 6 has its lower end 61 bent outwardly or

forwardly so as to be at one time engaged by the inner end of the ironing board 2 when the latter is swung downward into position of use.

At the beginning of the downward swing of the ironing board, its upper end first engages the clothes rack to swing it outwardly and upwardly. This movement raises the bar 6 until, by the time the ironing board 2 is about to clear the rack fingers 50, the inner end of the ironing board 2 engages beneath the foot 61 and completes the upper movement of rod 6. Rod 6, being connected with the frame 5 of the rack, will cause the latter to be swung upward into horizontal position. When not in use, the clothes rack will swing downwardly into the cabinet and lie just inwardly of or back of the ironing board 2.

It is desirable in many cases to provide means whereby the clothes rack may be maintained in raised position, even if the ironing board is folded up. This may be done by providing one of the guides 60, illustrated in Figure 3 as the uppermost of these guides, with a lock bolt 64, preferably held inward or in locking position by a spring, which bolt extends through a side wall of the guide 60 and is adapted to enter a notch formed in the side of the bar 6.

To provide means for insuring that the rack 50 shall be held in horizontal position when the ironing board is lowered, I have entered the upper end of the rod 6 within a socket in the head 63, which has the links or rods 66 journaled therein. A lock nut or bolt, as 65, which may be loosened when adjustment is desired, will enable the effective length of the parts, which hold the rack

raised, to be varied. If the rack has a tendency to sag down its outer ends, the adjustment of the holding bolt 65 may be such as

to lengthen the effective length of the rod 6, thereby raising the outer ends of the rack fingers 50.

An alternate or supplemental means for holding the rack in raised position may consist of a hook or hooks, as 67 which are mounted upon the pivot 51 of the rack frame and have their hooked ends engageable over the yoke or rods 66 by which the rack frame is supported. When so engaged, the ironing board may be folded into place without affecting the clothes rack.

In conjunction with the parts mentioned, a small or sleeve board 4 may be incorporated in the device. This board is supported by links 40 pivoted under the board and to the back of the casing. The inner end of this board may be inserted under a block or thrust member, as 41, also carried by the back of the casing. This may be readily folded back, and when in closed position, lie back of the ironing board 2.

What I claim as my invention is:

The combination with a wall cabinet of an ironing board pivoted to swing into the cabinet, a block secured to the under side of the board, a supporting leg for said board, a link pivoted to said leg a short distance downward from its upper end and to said block, said block and link being proportioned to abut the upper end of the leg against the inner end of the block when the leg is swung inward to form a diagonal supporting brace and against the outer end of the block when the leg is swung outwardly to form a vertical supporting leg, and a stop in the bottom of the cabinet engaged by the lower end of the brace when placed in said diagonal position.

Signed at Seattle, King County, Washington, this 19th day of March, 1927.

CHRISTIAN B. JOHNSON.
